UNITED STATES PATENT OFFICE.

HARRY T. LOOMIS, OF BROOKLYN, NEW YORK, ASSIGNOR TO FRANK AND LAMBERT, INC., OF NEW YORK, N. Y., A CORPORATION OF NEW YORK.

BURIAL-GARMENT.

1,170,293.

Specification of Letters Patent.

Patented Feb. 1, 1916.

Application filed May 13, 1915. Serial No. 27,762.

To all whom it may concern:

Be it known that I, HARRY T. LOOMIS, a citizen of the United States, and residing at Brooklyn, in the county of Kings and State of New York, have invented certain new and useful Improvements in Burial-Garments, of which the following is a specification, such as will enable those skilled in the art to which it appertains to make and use 10 the same.

This invention relates to burial garments and particularly to men's garments of this class, and the object thereof is to provide a garment of the class and for the purpose 15 specified which involves a coat and what is known as a foot pocket to receive the feet and legs, said coat and foot pocket being formed in connection and being preferably open at the back in the manner of ordinary 20 burial garments.

The invention is fully disclosed in the following specification, of which the accompanying drawing forms a part, in which the 25 separate parts of my improvement are designated by suitable reference characters in each of the views, and in which:—

Figure 1 is a front view of my complete burial garment, part of the foot pocket being broken away to show the back opening; 30 and, Fig. 2 a perspective side view indicating the method of using the garment.

In the practice of my invention, I provide a coat *a* and vest *b*, and the coat and vest may be separate, or the vest may be an 35 imitation garment connected with the coat, and said vest and coat are open at the back in the usual manner, and in connection with the coat I employ a foot pocket *c* to receive the feet and legs.

Copies of this patent may be obtained for five cents each, by addressing the "Commissioner of Patents, Washington, D. C."

The foot pocket *c* is connected with the bottom of the coat at *c*² and may be made of the same or any desired material, and said foot pocket is also open at the back longitudinally thereof, as shown at *c*³, and with my improvement the coat *a* is preferably made longer than is customary, at the present time, in making burial garments of this class.

One of the advantages of my improvement is that the foot pocket *c* holds the coat *a* in proper position and prevents it from slipping up, or working out of shape or position, and another advantage is that the application or use of a combination garment of this class made in this way is much more 50 simple and of much less trouble, and is also much less expensive than when garments of this class are made separate, as heretofore, and as will be understood any suitable 55 or desirable material may be used in making 60 my improved burial garment, or the separate parts thereof.

Having fully described my invention, what I claim as new and desire to secure by Letters Patent, is:—

In a burial garment, a coat and a foot pocket connected with the bottom edge portion of the coat and forming an extension thereof and adapted to receive the feet and legs, said coat and foot pocket being open 70 centrally of the back and approximately the full length thereof.

In testimony that I claim the foregoing as my invention I have signed my name this 11th day of May, 1915.

HARRY T. LOOMIS.
